UNITED STATES PATENT OFFICE.

THEODORE H. PROSKE, OF VICTOR, COLORADO.

SHARPENING-MACHINE FOR DRILL-BITS.

SPECIFICATION forming part of Letters Patent No. 692,796, dated February 4, 1902.

Application filed August 14, 1901. Serial No. 71,996. (No model.)

To all whom it may concern:

Be it known that I, THEODORE H. PROSKE, a citizen of the United States, and a resident of Victor, in the county of Teller and State 5 of Colorado, have invented a new and Improved Sharpening-Machine for Drill-Bits, of which the following is a full, clear, and exact description.

The object of the invention is to provide a 10 new and improved sharpening-machine for quickly and accurately fashioning and sharpening the bits of machine-drills and other drills, the sharpening-machine being simple and durable in construction, not liable to get 15 out of order, easily manipulated, and arranged to permit sharpening of drill-bits of various sizes.

The invention consists of novel features and parts and combinations of the same, as 20 will be fully described hereinafter and then pointed out in the claims.

A practical embodiment of the invention is represented in the accompanying drawings, forming a part of this specification, in which 25 similar characters of reference indicate corresponding parts in all the views.

Figure 1 is a side elevation of the improvement with a drill in position to be sharpened. Fig. 2 is a plan view of the same with the 30 drill shown broken out. Fig. 3 is an enlarged transverse section of the improvement on the line 3-3 in Fig. 1, showing more particularly the dies and the means for opening and closing the same. Fig. 4 is an enlarged side elevation of one of the dies and the dolly. Fig. 35 5 is a face view of the dolly-head. Fig. 6 is a front elevation of the trimming-machine for trimming the drill-bit previously to sharpening the same, and Fig. 7 is a side elevation 40 of the anvil and die of the trimming-machine.

The improved sharpening-machine is mounted on a suitably-constructed frame A, supporting a guide B, upon which a dolly C is loosely mounted to slide in a longitudinal direction, said dolly having radial wings C', terminating in a die-head C², formed on its face with a central shaping part C³ and with radially-extending bevels C⁴, as indicated in Figs. 4 and 5. The outsides of the wings C', 45 50 at the face of the dolly-head, form shears for cutting off any surplus material that may be on a wing of the drill-bit. The outer end of

the dolly C is adapted to be engaged by a reciprocating striker, such as the drill-chuck D of a drilling-machine of any approved construction, for imparting blows to the dolly C, and thereby fashioning and sharpening the drill-bit, as hereinafter more fully described. The shank of the chuck D is mounted to slide in suitable bearings E, attached to the frame 60 A, which latter also supports the rest of the drilling-machine. (Not shown.)

The bit F' of the drill F to be fashioned or sharpened is placed in an anvil-die G, while the end of the drill-shank rests on an abutment H, mounted to slide longitudinally in suitable bearings A', carried on the frame A. The die G is preferably made in sections G' G², (see Fig. 3,) held in boxes G³ G⁴, mounted to slide transversely in guideways A², attached to the frame A. The die-sections G' G² are preferably made square in cross-section, with part of a die on each face, and the die parts are of different sizes, so that when the sections G' G² are adjusted in the boxes 70 G³ G⁴ the die can be used for receiving drill-bits of various sizes, as will be readily understood by reference to Fig. 3. The die-sections besides forming stops for the drill-bit and part of the drill-shank (see Fig. 4) are 75 formed at their outer ends with bevels G⁵, located oppositely and operating, in conjunction with the bevels C⁴ on the dolly-head, to serve as a protection for the central shaping part C² of the dolly and to also serve as a 80 guide and bumper for the dolly.

The boxes G³ and G⁴ are engaged by screw-rods I I', each having right and left hand threads, so that upon turning said screw-rods the boxes G³ G⁴ are simultaneously moved toward or from each other to close or open the 85 die-sections G' G².

In order to rotate the screw-rods I I' simultaneously, I provide their outer ends with pinions I² I³ in mesh with a gear-wheel I⁴, 90 mounted to rotate on a stud I⁵, held on the bearing A², and on said gear-wheel I⁴ is secured a crank-arm I⁶ under the control of the operator. When the crank-arm I⁶ is turned in one direction, the die-sections G' G² are 95 moved to open the die for the insertion of the bit, and when the crank-arm I⁶ is turned in the opposite direction the die-sections G' G² close to hold the bit securely in position 100 dur-

ing the time the head C² of the dolly strikes the end of the bit and fashions the same according to the die G and at the same time sharpens the edges of the bit and removes the 5 surplus material that may be on the wings of the drill-bit. It is expressly understood that the seats in the die-sections G' G² have bevels G⁵ for engagement with the bevels C⁴ of the dolly-head to properly guide the latter to the 10 drill-bit and to insure accurate sharpening of the latter. The bevels C⁴ also serve to remove any surplus material that may be on the wings of the drill-bit.

The abutment H is engaged by a feed-screw 15 H', journaled in suitable bearings on the frame A and carrying a bevel gear-wheel H² in mesh with a bevel gear-wheel H³, mounted to turn in suitable bearings arranged on the frame A, adjacent to the bearing A². (See 20 Figs. 1 and 2.) On the outer end of the shaft H⁴ is secured a crank-arm H⁵, under the control of the operator, for turning the shaft H⁴ and imparting its rotary motion by the gear-wheels H³ H² to the feed-screw H', so that the 25 abutment H is moved toward or from the die G, according to the length of the drill under treatment at the time.

Prior to fashioning and sharpening the drill, it is necessary that the same be trimmed, and 30 for this purpose an anvil K is provided, (see Figs. 6 and 7,) over which operates a die L, connected with the reciprocating piston-rod of a drilling-machine to move the die toward or from said anvil K and cut the drill prior 35 to passing into the anvil-die G. It is understood that the drill is heated previously to trimming the same by the anvil K and the die

L, and while it is still in a hot condition it is placed in the anvil-die and acted upon by the dolly, as previously described, to give the desired shape and sharp cutting edges to the 40 drill-bit.

Having thus fully described my invention, I claim as new and desire to secure by Letters 45 Patent—

1. A sharpening-machine for drill-bits, comprising a die, and a dolly reciprocating toward and from said die, the die and the dolly having registering bevels to serve as a protection to the shaping part of the dolly and 50 as a guide and bumper for the same, as set forth.

2. A sharpening-machine for drill-bits, comprising a die provided with an operating-face bounded by angular edges, a dolly provided 55 with an operating-face mating said face of the die, and provided further with radially-disposed wings provided with cutting edges mating said angular edges of said die.

3. A sharpening-machine for drill-bits, comprising a die provided with an operating-face bounded by angular edges, a dolly having radially-disposed wings provided with an operating-face bounded by angular edges, the arrangement being such that said operating- 60 faces act as formers while said angular edges have a slight shearing movement.

In testimony whereof I have signed my name to this specification in the presence of two subscribing witnesses.

THEODORE H. PROSKE.
